UNITED STATES PATENT OFFICE.

EDWARD E. EVERETT, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA.

MOLD.

1,271,296.

Specification of Letters Patent. Patented July 2, 1918.

Application filed April 24, 1916. Serial No. 93,192.

To all whom it may concern:

Be it known that I, EDWARD E. EVERETT, a citizen of the United States, residing in Philadelphia, Pennsylvania, have invented 5 Molds, of which the following is a specification.

One object of my invention is to so construct a mold, particularly of the type designed for casting storage battery grids, that 10 it will effectively let out the air when the molten metal is poured into it, but shall prevent the escape of any of said metal.

This object and other advantageous ends 15 I secure as hereinafter set forth, reference being had to the accompanying drawings, in which:

Figure 1 is a transverse section of a mold constructed according to my invention; and

Fig. 2 is a plan of one of the sections of 20 the mold shown in Fig. 1.

In the above drawings 1 and 2 represent two relatively heavy metal plates or blocks constituting the two sections of a mold and positioned relatively to each other by pins 25 3 mounted on one section and extending into suitable recesses in the other. The abutting faces of said sections have formed in them cavities of the shape of the casting to be made and these are in communication with 30 an inlet chamber 4 into which the molten metal is poured.

In the case of the mold illustrated, the recesses in each mold section forming the entrance chamber have connected to them 35 grooves 5 and 6 which in turn are connected by other grooves 7 and 8 at right angles to them, which with said first grooves are intended for the reception of metal constituting the marginal portions of the grid. The 40 groove 6 has an extension 9 for the reception of metal designed to serve as the terminal of the grid and the grooves 5 and 6 are connected by smaller inclined grooves 10 so that the plate cast in the mold illustrated 45 is of the so-called "herring bone" construction.

Obviously other grooves similar to those shown in Fig. 2 are formed in that face of the section 2 of the mold which abuts upon 50 the grooved face of the section 1 and in either one of these sections (in the case illustrated that indicated at 2) there are formed a series of holes or passages 11 lead-

ing from its external face inwardly and opening on those portions of its flat inner 55 face which abut and practically contact with similar plane faces of the other mold section immediately adjacent the grooves but without communicating with any of the same in either section. It is noted that 60 the passages 11 are tapered or have their outer ends of larger diameter than that of their inner ends, so that if through incomplete closure of the mold, metal should enter and harden in them, it could be easily 65 removed.

With this arrangement of parts when the mold sections have been fastened together, and usually heated, the molten metal is delivered to the inlet chamber 4 from which it 70 freely flows to the various grooves. These are filled with air, which unless allowed to escape, would impede the flow of the metal and cause imperfect castings, and the molten metal forces it out through the relatively 75 thin spaces between the abutting faces of the mold sections into the passages 11 which open on said faces. These spaces between the mold sections, while permitting the rapid discharge of air from the grooves, 80 are of such minute thickness as to absolutely prevent the entrance of said metal from said grooves and the terminal chamber 9. The metal is thus permitted to quickly reach and fill all spaces in the mold 85 which are in communication with the entrance chamber 4, but is effectually prevented from trapping any of the air in the mold and the consequent formation of imperfect frame or lattice-work members in the finished grid. 90

Obviously it is immaterial whether both or but one or more than two mold sections are formed with metal receiving cavities, since the vital feature of my invention resides in the provision of air vents leading to or opening upon one face of a mold section which abuts upon another face adjacent a metal receiving cavity so as to allow escape of the air through the minute spaces 100 between said contacting faces without possibility of permitting flow of metal therethrough.

I claim:

A mold made in sections having flat contacting faces and provided with cavities in

the form of grooves defining closed figures, at least one of said sections being provided with air vents opening on portions of the flat inner face thereof circumscribed by the 5 grooves and abutting against flat portions of another section, which portions while

substantially engaging the first section, provide with it relatively thin passages whose dimensions are insufficient to allow of flow of metal but which allow escape of air from 10 the mold cavities.

EDWARD E. EVERETT.
